T. A. KILLMAN

MOVING PICTURE TOY

Filed June 13, 1925

UNITED STATES PATENT OFFICE.

THOMAS A. KILLMAN, OF NASHVILLE, TENNESSEE, ASSIGNOR OF ONE-HALF TO
THOMAS G. WATKINS, OF NASHVILLE, TENNESSEE.

MOVING-PICTURE TOY.

Application filed June 13, 1925. Serial No. 36,888.

To all whom it may concern:

Be it known that I, THOMAS A. KILLMAN, a citizen of the United States, residing at Nashville, in the county of Davidson and 5 State of Tennessee, have invented certain new and useful Improvements in Moving-Picture Toys, of which the following is a specification.

This invention relates to toys and more 10 particularly to a moving picture toy.

The general object of the invention is to provide a very simple moving picture toy of such character that it will carry a plurality of radially disposed pictures arranged 15 in consecutive order and so mounted that the toy may be placed between the fingers and twirled about so that the pictures may be consecutively seen, the different positions of the objects in the several pictures being 20 so presented that the figures will seem to move.

A further object of the invention is to provide a toy of this kind having a spindle so formed that as the spindle is twirled between the thumbs and fingers of the two hands, the device will be given an intermittent rotary movement which will cause the objects in the pictures to seem to move in a very natural and life-like manner just as 25 they would when projected by a regular motion picture machine.

A further object is to provide a device of this character which is particularly adapted for carrying advertising matter and 30 which may be very cheaply produced.

My invention is illustrated in the accompanying drawing, wherein:

Figure 1 is a face view of my moving picture toy showing the manner in which it is 40 manipulated;

Figure 2 is an end elevation of the toy;

Figure 3 is an elevation of the barrel 10 but with the cards or vanes removed;

Figure 4 is a section on the line 4—4 of 45 Figure 3.

Referring to the drawings, it will be seen that my improved toy comprises a rod or shaft 10 which may be formed of wood or any other suitable material and which is 50 formed with a plurality of longitudinally extending grooves 11 opening upon the beveled faces 12 of this barrel or central shaft. Extending from the ends of these 55 beveled faces 12 are portions 13 which are rectangular in cross section and relatively

thin and from these portions 13 extend the gudgeons 14. Disposed within the grooves 11 are the radiating cards 15 which carry upon their faces the representations of objects or bodies in action. One face of the 60 card may carry a picture 16 while the opposite face of the card may carry advertising matter, as at 17. It will be understood, of course, that the pictures at 16 are consecutive pictures, or in other words, the same 65 objects are disposed on the various pictures 16 but the objects are changed in position, these positions representing the positions that any animate or moving object would naturally take in performing any natural 70 cycles of movements. Thus card No. 1 shows the objects in a certain position and on card No. 2, the position is slightly changed and so on through the series of 75 cards, the series of cards showing some simple movement of the object.

The operation of this device is as follows:—The cards are inserted in the grooves formed in the shaft in the order in which they are printed. They will then radiate outward and be approximately ninety degrees from each other around the shaft. In use, one of the small pins or gudgeons 14 is disposed in the bend of the first joint of the forefinger as, for instance, the right hand, this bend acting as a bearing for the gudgeon to revolve in. The other gudgeon 14 occupies a like position in the left hand. The thumbs of both hands rest lightly on the spindles 13 with the right 90 thumb for instance resting on the flat face of the spindle while the left thumb rests on the edge of the corresponding spindle.

In order to cause the device to rotate, the left thumb is pressed down on the edge of 95 the corresponding spindle and at the same time gives to the spindle a slight twirling motion while the right thumb is slightly raised to permit the shaft to revolve. The left thumb is pressed down until it rests on the flat face of the spindle at this end 100 which will cause the shaft to stop momentarily. Then the right thumb at this time will rest on the edge of the right hand spindle and is pressed down on this edge at the same time, giving it a slight twirling motion and, of course, in the same direction as before until it rests upon the flat surface 105 of the spindle. The right and left thumbs thus operate alternately in this manner giv-

ing the device an intermittent rotary movement which will permit each picture to become stationary for a fraction of a second and then the device will move so as to bring 5 another picture into the line of vision. Thus the movable objects in the pictures will seem to move in a very natural and lifelike manner just as they do when projected by a regular motion picture machine.

10 It is obvious that the scenes or pictures which will be suitable for use on a toy of this character are practically unlimited even though these pictures must be simple. Thus, for instance, the device may be used 15 for showing moving pictures of billy goats fighting; fighting roosters, boxing matches, marching soldiers, etc. Obviously, the advertisements 17 may be left off entirely and moving pictures used on opposite sides of 20 the radiating cards and brought into proper position by simply reversing the ends of the shaft. Obviously, also minor changes might be made in the details of construction without departing from the spirit of the in- 25vention.

I claim:

1. A toy of the character described comprising a shaft carrying radiating vanes, the vanes carrying upon their faces a series 30 of consecutive pictures, the shaft at its ends being formed with spindles, each spindle being relatively narrow in one dimension to provide two opposed relatively wide flat faces and two opposed relatively thin faces 35 intermediate the wide flat faces.

2. A toy of the character described comprising a shaft carrying a plurality of radiating vanes, the vanes carrying upon

their faces a series of consecutive pictures showing objects in motion, the shaft at its 40 ends being formed to provide opposite spindles, each spindle being relatively narrow in one dimension to provide two opposed relatively wide flat faces and two opposed relatively narrow faces intermediate the wide flat faces and the spindles carrying gudgeons projecting beyond the 45 spindles.

3. A toy of the character described comprising a shaft beveled at its ends and longitudinally grooved to receive a plurality of radiating vanes, the vanes carrying a series of consecutive pictures of moving objects, spindles projecting from the extremities of the shaft, each spindle being relatively wide 50 in one dimension transversely of the axis of the spindle and relatively narrow in the dimension at right angles to the first named dimension and to the axis of the spindle to thereby provide opposed relatively wide 55 faces and opposed relatively narrow faces and gudgeons projecting beyond the spindle.

4. A moving picture toy of the character described comprising a shaft carrying a plurality of radiating vanes having thereon 60 a series of consecutive pictures of moving objects, the shaft being extended to provide means for holding the shaft and said extensions being formed to provide alternate wide flat faces and narrow rounded faces 65 extending parallel to the axis of the shaft whereby the shaft is twirled by the fingers, the shaft will be given an intermittent 70 rotary movement.

In testimony whereof I affix my signature.
THOMAS A. KILLMAN.
